Frank Dvorsky

BY *Marvin Palmit*
ATTORNEY

UNITED STATES PATENT OFFICE.

FRANK DVORSKY, OF NEW YORK, N. Y.

AUTOMATIC CIGAR AND CIGARETTE BOX.

Application filed May 13, 1925. Serial No. 29,864.

To all whom it may concern:

Be it known that I, FRANK DVORSKY, a citizen of the United States, residing at New York, in the county of New York and State 5 of New York, have invented certain new and useful Improvements in Automatic Cigar and Cigarette Boxes, of which the following is a specification.

This invention relates to improvements in 10 dispensing containers for cigars, cigarettes and like small cylindrical objects, having among its several objects to provide an attractive novelty capable of containing a quantity of loose articles of like nature and 15 convey them, one at a time, into an accessible position.

A further feature is in the provision of a 20 container surmounted by a figure representing an animal, as for instance, an elephant, having movable parts which co-operate with other parts of the structure in delivering the articles.

Another object is in the production of a 25 dispensing container operated manually by the depression of a single key whereby one article is segregated from the supply source into position for use, the parts thereafter returning to their original position automatically.

These objects are attained by the present 30 construction and arrangement of members hereinafter described and delineated in the associated drawings, a constituent part of this exposition, and in which:—

Figure 1 is a partial side elevational, partial sectional view of an embodiment of the 35 invention, the section being taken in a plane represented by the line 1—1 of Figure 4.

Figure 2 is a similar view of the same, but 40 showing the parts in a position assumed in the earlier stage of their operation.

Figure 3 is another like view showing the 45 structure in its delivery position.

Figure 4 is a transverse sectional view 50 taken on line 4—4 of Figure 2, the animal figure being omitted.

Referring in greater detail to the several 55 views, the numeral 10 designates the flooring or bottom wall of a box-like structure, having similar sides 11, rear end 12 and front wall 13 offset inwardly as at 14 at its upper portion, opposite to which is an angularly inclined wall extending from the cover 16.

Midway in the cover is a hinged plate 17 to be raised in replenishing the contents of 55 the container when desired.

A similarly but angularly disposed plate 18 is hinged to the front wall 14 and extends, when closed to the plate 15, the sides 11 being shaped in conformity with these 60 plates.

Fixed to extend between the walls 11, below the door 17, is a plate 19 inclined downwardly towards the front and connected by a rear wall 20 to the cover 16. 65

A shutter plate 21 extends angularly downward and towards the front from the intersection of the cover 16 and plate 15, there being a space between the lower edge of the plates 21 and 19 to permit passage of 70 the articles 22 to be dispensed, these articles moving towards the front, over the plate 19, by gravity.

Fixed on the bottom, towards the front, are a pair of opposed brackets 23 in which 75 are revolvably mounted spindles 24 and 25, the latter upper spindle carrying a roll 26 to which is attached a pair of spaced arms 27 having inreaching loops 28 from which extend arcuately bent finder elements 29. 80

As seen in Figures 1 and 2, the loops 28 are so disposed as to receive one of the articles 22, and the fenders 29 prevent other articles from delivery, as seen in Figure 3.

Midway in the length of the roll 26 are 85 a pair of raised extensions 30 to which are attached tension springs 31 and fixed to the extensions is a loop 32, the opposite ends of the spring being fixed to some stationary part of the brackets. 90

The spindle 24 carries a grooved pulley 33 over which is trained a cord 34, one end being attached to the junction of the extensions 30 at the bottom of the loop 32, and the other end of the cord carried over a 95 pulley 35 rotatable in a bracket 36 at the rear end of the structure, the terminal of the cord being fixed to the lower end of a plunger 37.

The plunger 37 is provided with a finger 100 pad 38 at its upper end, which extends through the cover 16 and is held normally raised by a coiled compression spring 39 encircling the extending portion of the plunger rod. 105

The lower end of the rod has a fixed pad

40 adapted to contact with a stop 41 set in the bottom to limit the downward movement of the plunger.

5 A pair of lever arms 42, pivoted at 43, are normally drawn upward by tension springs 44, these arms being displaceable by the plunger as it is moved down.

Attached to the free end of the arms 42 are links 45 pivotally connected at 46 to link 10 extensions 47 in turn operatively connected to the front cover or door 18.

A short rod 48 is fixed transversely in the plunger rod 37, acting as a stop to limit its rise by making contact with the cover 16, 15 and secured to the inner end of the rod 48 is a flexible wire 49 extending up through the cover into the leg of a figure representing an elephant 50.

The figure is hollow and has mounted in 20 it a pulley 51 over which the wire is trained and coiled into a spring 52, a continuation 53 of which is secured to a lever 54, pivoted at 55 in the head of the figure, this pivot also connecting the trunk 56 of the elephant.

25 A continuation of the lever 54 engages the hollow trunk, and the opposite end 58 of the lever is engaged by a tension spring 59, having its opposite end fixed in the body of the figure.

30 The end of the trunk 56 is highly flexible and used to retain one of the articles 22, as at 60 in Figure 3, in the loops 28 when in operation, the trunk normally coiling due to its elastic nature, until straightened by 35 contact with the spring drawn loop 32.

In operation, the reservoir is filled by raising the door, the curved finders 29 preventing the articles from premature dispensation.

40 Upon depressing the plunger knob 38 the door 18 will first be raised and thereafter, in sequence the dispensing device raised,

carrying a single article upward to be held in the loops 28 until manually removed, whereupon releasing the plunger knob all 45 parts return to their normal position and the elephant trunk is raised by the spring 59, assuming the position shown in Figure 1.

From the foregoing it will be seen that an attractive, novel and practical device has 50 been disclosed that is capable of fulfilling the several purposes set forth.

Having thus described my invention, together with its construction and operation, what I claim as new and desire to secure by 55 Letters Patent, is:—

A dispensing container comprising a casing, a figural object on the cover of said casing, said object having a single elongated member pivoted to the body, terminating in a normally coiled flexible element, means in said object to normally retain said member in a raised position, an article holding receptacle engaged in said casing, said casing having a filling door, a hinged delivery door disposed in the path of said member, means for opening said delivery door, means for delivering a single article from said receptacle to the door, a plunger operatively engaged with the delivery door opening means and with said article delivering means, operative connections between said plunger and the pivoted member of said figural object, to lower said member, means actuated by said plunger to uncoil said flexible element and thereafter permit it to engage an article on said delivery means, and means for returning all of said parts to their initial position upon release of said plunger.

80 In witness whereof I have affixed my signature.

FRANK DVORSKY.
